UNITED STATES PATENT OFFICE.

FRANK O. HOAGLAND, OF BRIDGEPORT, CONNECTICUT, ASSIGNOR TO PRATT & WHITNEY COMPANY, OF NEW YORK, N. Y., A CORPORATION OF NEW JERSEY.

LAPPING MACHINE.

Application filed September 15, 1918. Serial No. 322,736.

To all whom it may concern:

Be it known that I, FRANK O. HOAGLAND, a citizen of the United States, residing at Bridgeport, in the county of Fairfield and State of Connecticut, have invented certain new and useful Improvements in Lapping Machines, of which the following is a specification.

This invention relates to machines for accurately lapping the inside surfaces of cylindrical holes. One of the objects of the invention is to provide a rotating cylindrical lap and automatic means for effecting relative reciprocations between the lap and the work. Another object of the invention is to provide automatic means for applying abrasive to the lap at suitable intervals. Further objects of the invention will be apparent from the following specification and claims.

Of the drawings:

Fig. 1 is a front view of the machine.

Fig. 2 is a longitudinal sectional view taken along the center line of the machine.

Fig. 3 is a left end view.

Fig. 4 is a right end view.

Fig. 5 is a fragmentary sectional view taken along the line 5—5 of Fig. 4.

Figs. 6 and 7 are front and side views respectively of the carrier for the cam followers.

Figs. 8 and 9 are front and side views respectively of the worm wheel and cams assembled in the relative positions they occupy in the machine.

Figs. 10, 11 and 12 are front, side and plan views respectively of the member forming two cam followers.

Fig. 13 is a rear view of the gear and cam segments for operating the abrasive applying mechanism.

Referring to the drawings, 1 represents the bed of the machine and 2 and 3 respectively represent the tool-carrying headstock and the work-carrying tailstock mounted on the bed.

Rotatably mounted in the headstock is a spindle 4 which carries tight and loose belt pulleys 5 and 6. A belt shifter 7 is provided for shifting a drive belt to either of the pulleys 5 and 6. The spindle 4 is adapted to receive and drive a cylindrical or conical lap 8, which is preferably split as shown and which corresponds in diameter or shape to the hole to be lapped. Prefer-

ably, as shown, the end of the spindle is provided with left-hand threads at 4^a which serve to prevent abrasive from entering the spindle bearings.

Carried by the tailstock is a suitable work holder 9 which is preferably of the magnetic type. The details of the work holder constitute no part of the invention and are not illustrated. Fig. 1 shows a piece of work A held by the work holder 9. In order that lapping may be effected, it is necessary to effect relative reciprocation between the lap and the work. For this purpose I provide a spindle or plunger 10 which is longitudinally reciprocable in the tailstock and which carries the work holder 9. The plunger is recessed at 10^a to clear the end of the lap 8. Holes 10^b—10^b communicate with the recess 10^a for a purpose hereinafter described. It will be understood that ordinarily the spindles 4 and 10 are coaxial as shown in the drawing, although the invention is not limited in this respect. The mechanism for reciprocating the plunger will now be described.

A compression coil spring 11 is provided which normally tends to hold the plunger in its left-hand position. This spring is mounted in a central recess in the plunger and at its left-hand end abuts against a collar on a threaded rod 12. The other end of the spring abuts against a collar 13 which is engaged by screws 14 projecting through slots 15 in the sides of the plunger. The rod 12 is threaded into a bushing 16 secured to the plunger and the rod can be turned by means of a knob 17. It will be seen that by turning the rod the tension of the spring can be varied as desired.

For drawing the plunger and the work holder backward against the spring action there is provided a cam, or preferably two cams, carried by a transverse rotatable shaft 18 mounted in the tailstock. Preferably the shaft 18 is rotated by means of a centrally disposed worm wheel 19 and two cams 20 and 21 are directly connected with the worm wheel at opposite sides thereof. Rigidly secured to the plunger 10 is a carrier member 22 upon which is mounted one, or preferably two, cam followers. As illustrated, the carrier member 22 is provided with a transverse T-slot 23 in which is fitted the cross bar 24 of a combined follower element shown in detail in Figs. 10, 11 and 12. This

follower element includes a follower 25 adapted to be engaged by the cam 20 and a follower 26 adapted to be engaged by the cam 21. The follower element is transversely adjustable with respect to the carrier 22, being movable in the T-slot 23. This transverse movement enables follower 25 or 26 to be brought into operative relation respectively with the corresponding cam 20 or 21. 10 The follower element can be locked in either position by means of a set screw 26a. As illustrated, the cam 20 has one lobe and the cam 21 has three small lobes and one large lobe. It will be seen that when the cam 20 15 is in use the plunger and the work holder will be regularly reciprocated. When the cam 21 is in use the plunger and work holder will be given three short reciprocations followed by one longer one. The purpose of 20 these different reciprocations will be hereinafter set forth.

In order that the reciprocations of the plunger 10 may be stopped without stopping the operations of the other parts of the 25 machine, there is provided a latch 27 which is adapted to engage the carrier member 22 when the plunger with the said carrier member is withdrawn to a position just beyond the limit of normal reciprocation. It 30 will be seen that by thus withdrawing and latching the plunger and carrier member, the reciprocation of the work is stopped without, however, interfering with any of the other machine operations.

35 The worm wheel 19 meshes with a worm 28 which is connected with a longitudinal shaft 29. Suitable mechanism is provided for rotating the shaft 29, this mechanism as shown including intermeshing gears 30, 31 40 and 32 which connect the shaft with the spindle 4. It will therefore be seen that the tool or lap spindle 4 is rotated in a definite timed relation to the reciprocation of the work spindle 10. This relation assures a 45 definite number of rotations of thelapping tool 8 to each relative reciprocation between the tool and work. Such definite relative movement between the tool and work provides a smoother and more accuratelapping 50 of the work than can be otherwise obtained.

55 Preferably the tailstock is bodily adjustable on the bed and the power transmitting connections for the worm 28 are so constructed as to make this adjustment possible when the machine is in operation. As 60 illustrated, the worm 28 is not mounted directly upon the shaft 29, but is formed as a part of a sleeve 33 which has telescopic splined engagement with the shaft. It will be seen that this construction permits the tailstock to be adjusted longitudinally without interfering with the power connection.

65 In order that the tailstock may be conveniently moved, it is provided with a rack 34 which meshes with a pinion 35 on a

transverse shaft 36. At the front end of the shaft is a knob 37 whereby the shaft may be conveniently turned to move the tailstock. For clamping the tailstock in adjusted position there is provided a locking bolt 38 which extends through the tailstock and is provided at its rear end with a head 39 engaging a bearing surface 40 on the bed. A knob 41 is threaded on the front end of the bolt 38 and by turning this knob 75 the bolt can be tightened to clamp the tailstock in adjusted position.

I provide automatic mechanism for applying abrasive to the lap 8. As illustrated, a pan or reservoir 42 is provided on the tailstock for holding abrasive paste. An oscillatory shaft 43 is mounted on the rear of the machine and a spoon or ladle 44 is connected with the shaft by means of a resiliently mounted arm 45. The arm can be adjusted 80 along the shaft as desired and can be held by a set screw 45a. The spoon is so positioned that it oscillates between the pan 42 and the lap 8, the resilient mounting of the arm 45 serving to provide a yielding pressure between the spoon and the lap. The shaft 43 is mounted in bearing brackets 46 and 47 carried respectively by the plunger 10 and by the tailstock frame. Collars are provided at each side of the bearing 46 and as this bearing reciprocates with the plunger 85 the shaft 43 also reciprocates, carrying the spoon with it. At the bearing 46 is a spring 48 which serves to rock the shaft in the counter clockwise direction, thus tending to hold the spoon in its lowermost position in the pan. Mounted at the rear end of the before mentioned rotatable shaft 18 is a pinion 49 which meshes with a gear 50, the ratio 90 between the gears 49 and 50, as illustrated, being 4 to 1. One or more similar cam segments 51 are mounted on the rear face of the gear 50. As illustrated, there are four such segments, but it will be understood 95 that one or more of these may be removed when desired. Splined to the right-hand end of the shaft 43 is an arm 52 which is adapted to be engaged by the segments 51 as the gear 50 rotates. Inasmuch as the ratio 100 between the gears 49 and 50 is 4 to 1, it will be seen that when all four cam segments are in place the arm 52 and the shaft 43 will be actuated once for each revolution of the shaft 18 and therefore once for each reciprocation of the plunger 10. Therefore the spoon or ladle 44 will transfer a charge of abrasive from the pan to the lap at each reciprocation of the work. By removing alternate cams 51 the ladle can be made to 105 operate at each alternate reciprocation; or by removing all but one of the cams the ladle can be made to operate at every fourth reciprocation. It will be seen that inasmuch 110 as the spoon reciprocates with the work the abrasive is always applied at the same dis-

115 tance from the work. The spoon 44 is provided with a slot 53 which is closed by a cover 54. The cover 54 is held in place by a set screw 55. The cover 54 is provided with a slot 56 which is closed by a cover 57. The cover 57 is held in place by a set screw 58. The cover 57 is provided with a slot 59 which is closed by a cover 60. The cover 60 is held in place by a set screw 61. The cover 60 is provided with a slot 62 which is closed by a cover 63. The cover 63 is held in place by a set screw 64. The cover 63 is provided with a slot 65 which is closed by a cover 66. The cover 66 is held in place by a set screw 67. The cover 66 is provided with a slot 68 which is closed by a cover 69. The cover 69 is held in place by a set screw 70. The cover 69 is provided with a slot 71 which is closed by a cover 72. The cover 72 is held in place by a set screw 73. The cover 72 is provided with a slot 74 which is closed by a cover 75. The cover 75 is held in place by a set screw 76. The cover 75 is provided with a slot 77 which is closed by a cover 78. The cover 78 is held in place by a set screw 79. The cover 78 is provided with a slot 80 which is closed by a cover 81. The cover 81 is held in place by a set screw 82. The cover 81 is provided with a slot 83 which is closed by a cover 84. The cover 84 is held in place by a set screw 85. The cover 84 is provided with a slot 86 which is closed by a cover 87. The cover 87 is held in place by a set screw 88. The cover 87 is provided with a slot 89 which is closed by a cover 90. The cover 90 is held in place by a set screw 91. The cover 90 is provided with a slot 92 which is closed by a cover 93. The cover 93 is held in place by a set screw 94. The cover 93 is provided with a slot 95 which is closed by a cover 96. The cover 96 is held in place by a set screw 97. The cover 96 is provided with a slot 98 which is closed by a cover 99. The cover 99 is held in place by a set screw 100. The cover 99 is provided with a slot 101 which is closed by a cover 102. The cover 102 is held in place by a set screw 103. The cover 102 is provided with a slot 104 which is closed by a cover 105. The cover 105 is held in place by a set screw 106. The cover 105 is provided with a slot 107 which is closed by a cover 108. The cover 108 is held in place by a set screw 109. The cover 108 is provided with a slot 110 which is closed by a cover 111. The cover 111 is held in place by a set screw 112. The cover 111 is provided with a slot 113 which is closed by a cover 114. The cover 114 is held in place by a set screw 115. The cover 114 is provided with a slot 116 which is closed by a cover 117. The cover 117 is held in place by a set screw 118. The cover 117 is provided with a slot 119 which is closed by a cover 120. The cover 120 is held in place by a set screw 121. The cover 120 is provided with a slot 122 which is closed by a cover 123. The cover 123 is held in place by a set screw 124. The cover 123 is provided with a slot 125 which is closed by a cover 126. The cover 126 is held in place by a set screw 127. The cover 126 is provided with a slot 128 which is closed by a cover 129. The cover 129 is held in place by a set screw 130. The cover 129 is provided with a slot 131 which is closed by a cover 132. The cover 132 is held in place by a set screw 133. The cover 132 is provided with a slot 134 which is closed by a cover 135. The cover 135 is held in place by a set screw 136. The cover 135 is provided with a slot 137 which is closed by a cover 138. The cover 138 is held in place by a set screw 139. The cover 138 is provided with a slot 140 which is closed by a cover 141. The cover 141 is held in place by a set screw 142. The cover 141 is provided with a slot 143 which is closed by a cover 144. The cover 144 is held in place by a set screw 145. The cover 144 is provided with a slot 146 which is closed by a cover 147. The cover 147 is held in place by a set screw 148. The cover 147 is provided with a slot 149 which is closed by a cover 150. The cover 150 is held in place by a set screw 151. The cover 150 is provided with a slot 152 which is closed by a cover 153. The cover 153 is held in place by a set screw 154. The cover 153 is provided with a slot 155 which is closed by a cover 156. The cover 156 is held in place by a set screw 157. The cover 156 is provided with a slot 158 which is closed by a cover 159. The cover 159 is held in place by a set screw 160. The cover 159 is provided with a slot 161 which is closed by a cover 162. The cover 162 is held in place by a set screw 163. The cover 162 is provided with a slot 164 which is closed by a cover 165. The cover 165 is held in place by a set screw 166. The cover 165 is provided with a slot 167 which is closed by a cover 168. The cover 168 is held in place by a set screw 169. The cover 168 is provided with a slot 170 which is closed by a cover 171. The cover 171 is held in place by a set screw 172. The cover 171 is provided with a slot 173 which is closed by a cover 174. The cover 174 is held in place by a set screw 175. The cover 174 is provided with a slot 176 which is closed by a cover 177. The cover 177 is held in place by a set screw 178. The cover 177 is provided with a slot 179 which is closed by a cover 180. The cover 180 is held in place by a set screw 181. The cover 180 is provided with a slot 182 which is closed by a cover 183. The cover 183 is held in place by a set screw 184. The cover 183 is provided with a slot 185 which is closed by a cover 186. The cover 186 is held in place by a set screw 187. The cover 186 is provided with a slot 188 which is closed by a cover 189. The cover 189 is held in place by a set screw 190. The cover 189 is provided with a slot 191 which is closed by a cover 192. The cover 192 is held in place by a set screw 193. The cover 192 is provided with a slot 194 which is closed by a cover 195. The cover 195 is held in place by a set screw 196. The cover 195 is provided with a slot 197 which is closed by a cover 198. The cover 198 is held in place by a set screw 199. The cover 198 is provided with a slot 200 which is closed by a cover 201. The cover 201 is held in place by a set screw 202. The cover 201 is provided with a slot 203 which is closed by a cover 204. The cover 204 is held in place by a set screw 205. The cover 204 is provided with a slot 206 which is closed by a cover 207. The cover 207 is held in place by a set screw 208. The cover 207 is provided with a slot 209 which is closed by a cover 210. The cover 210 is held in place by a set screw 211. The cover 210 is provided with a slot 212 which is closed by a cover 213. The cover 213 is held in place by a set screw 214. The cover 213 is provided with a slot 215 which is closed by a cover 216. The cover 216 is held in place by a set screw 217. The cover 216 is provided with a slot 218 which is closed by a cover 219. The cover 219 is held in place by a set screw 220. The cover 219 is provided with a slot 221 which is closed by a cover 222. The cover 222 is held in place by a set screw 223. The cover 222 is provided with a slot 224 which is closed by a cover 225. The cover 225 is held in place by a set screw 226. The cover 225 is provided with a slot 227 which is closed by a cover 228. The cover 228 is held in place by a set screw 229. The cover 228 is provided with a slot 230 which is closed by a cover 231. The cover 231 is held in place by a set screw 232. The cover 231 is provided with a slot 233 which is closed by a cover 234. The cover 234 is held in place by a set screw 235. The cover 234 is provided with a slot 236 which is closed by a cover 237. The cover 237 is held in place by a set screw 238. The cover 237 is provided with a slot 239 which is closed by a cover 240. The cover 240 is held in place by a set screw 241. The cover 240 is provided with a slot 242 which is closed by a cover 243. The cover 243 is held in place by a set screw 244. The cover 243 is provided with a slot 245 which is closed by a cover 246. The cover 246 is held in place by a set screw 247. The cover 246 is provided with a slot 248 which is closed by a cover 249. The cover 249 is held in place by a set screw 250. The cover 249 is provided with a slot 251 which is closed by a cover 252. The cover 252 is held in place by a set screw 253. The cover 252 is provided with a slot 254 which is closed by a cover 255. The cover 255 is held in place by a set screw 256. The cover 255 is provided with a slot 257 which is closed by a cover 258. The cover 258 is held in place by a set screw 259. The cover 258 is provided with a slot 260 which is closed by a cover 261. The cover 261 is held in place by a set screw 262. The cover 261 is provided with a slot 263 which is closed by a cover 264. The cover 264 is held in place by a set screw 265. The cover 264 is provided with a slot 266 which is closed by a cover 267. The cover 267 is held in place by a set screw 268. The cover 267 is provided with a slot 269 which is closed by a cover 270. The cover 270 is held in place by a set screw 271. The cover 270 is provided with a slot 272 which is closed by a cover 273. The cover 273 is held in place by a set screw 274. The cover 273 is provided with a slot 275 which is closed by a cover 276. The cover 276 is held in place by a set screw 277. The cover 276 is provided with a slot 278 which is closed by a cover 279. The cover 279 is held in place by a set screw 280. The cover 279 is provided with a slot 281 which is closed by a cover 282. The cover 282 is held in place by a set screw 283. The cover 282 is provided with a slot 284 which is closed by a cover 285. The cover 285 is held in place by a set screw 286. The cover 285 is provided with a slot 287 which is closed by a cover 288. The cover 288 is held in place by a set screw 289. The cover 288 is provided with a slot 290 which is closed by a cover 291. The cover 291 is held in place by a set screw 292. The cover 291 is provided with a slot 293 which is closed by a cover 294. The cover 294 is held in place by a set screw 295. The cover 294 is provided with a slot 296 which is closed by a cover 297. The cover 297 is held in place by a set screw 298. The cover 297 is provided with a slot 299 which is closed by a cover 300. The cover 300 is held in place by a set screw 301. The cover 300 is provided with a slot 302 which is closed by a cover 303. The cover 303 is held in place by a set screw 304. The cover 303 is provided with a slot 305 which is closed by a cover 306. The cover 306 is held in place by a set screw 307. The cover 306 is provided with a slot 308 which is closed by a cover 309. The cover 309 is held in place by a set screw 310. The cover 309 is provided with a slot 311 which is closed by a cover 312. The cover 312 is held in place by a set screw 313. The cover 312 is provided with a slot 314 which is closed by a cover 315. The cover 315 is held in place by a set screw 316. The cover 315 is provided with a slot 317 which is closed by a cover 318. The cover 318 is held in place by a set screw 319. The cover 318 is provided with a slot 320 which is closed by a cover 321. The cover 321 is held in place by a set screw 322. The cover 321 is provided with a slot 323 which is closed by a cover 324. The cover 324 is held in place by a set screw 325. The cover 324 is provided with a slot 326 which is closed by a cover 327. The cover 327 is held in place by a set screw 328. The cover 327 is provided with a slot 329 which is closed by a cover 330. The cover 330 is held in place by a set screw 331. The cover 330 is provided with a slot 332 which is closed by a cover 333. The cover 333 is held in place by a set screw 334. The cover 334 is provided with a slot 335 which is closed by a cover 336. The cover 336 is held in place by a set screw 337. The cover 336 is provided with a slot 338 which is closed by a cover 339. The cover 339 is held in place by a set screw 340. The cover 339 is provided with a slot 341 which is closed by a cover 342. The cover 342 is held in place by a set screw 343. The cover 342 is provided with a slot 344 which is closed by a cover 345. The cover 345 is held in place by a set screw 346. The cover 346 is provided with a slot 347 which is closed by a cover 348. The cover 348 is held in place by a set screw 349. The cover 349 is provided with a slot 350 which is closed by a cover 351. The cover 351 is held in place by a set screw 352. The cover 352 is provided with a slot 353 which is closed by a cover 354. The cover 354 is held in place by a set screw 355. The cover 355 is provided with a slot 356 which is closed by a cover 357. The cover 357 is held in place by a set screw 358. The cover 358 is provided with a slot 359 which is closed by a cover 360. The cover 360 is held in place by a set screw 361. The cover 361 is provided with a slot 362 which is closed by a cover 363. The cover 363 is held in place by a set screw 364. The cover 364 is provided with a slot 365 which is closed by a cover 366. The cover 366 is held in place by a set screw 367. The cover 367 is provided with a slot 368 which is closed by a cover 369. The cover 369 is held in place by a set screw 370. The cover 370 is provided with a slot 371 which is closed by a cover 372. The cover 372 is held in place by a set screw 373. The cover 373 is provided with a slot 374 which is closed by a cover 375. The cover 375 is held in place by a set screw 376. The cover 376 is provided with a slot 377 which is closed by a cover 378. The cover 378 is held in place by a set screw 379. The cover 379 is provided with a slot 380 which is closed by a cover 381. The cover 381 is held in place by a set screw 382. The cover 382 is provided with a slot 383 which is closed by a cover 384. The cover 384 is held in place by a set screw 385. The cover 385 is provided with a slot 386 which is closed by a cover 387. The cover 387 is held in place by a set screw 388. The cover 388 is provided with a slot 389 which is closed by a cover 390. The cover 390 is held in place by a set screw 391. The cover 391 is provided with a slot 392 which is closed by a cover 393. The cover 393 is held in place by a set screw 394. The cover 394 is provided with a slot 395 which is closed by a cover 396. The cover 396 is held in place by a set screw 397. The cover 397 is provided with a slot 398 which is closed by a cover 399. The cover 399 is held in place by a set screw 400. The cover 400 is provided with a slot 401 which is closed by a cover 402. The cover 402 is held in place by a set screw 403. The cover 403 is provided with a slot 404 which is closed by a cover 405. The cover 405 is held in place by a set screw 406. The cover 406 is provided with a slot 407 which is closed by a cover 408. The cover 408 is held in place by a set screw 409. The cover 409 is provided with a slot 410 which is closed by a cover 411. The cover 411 is held in place by a set screw 412. The cover 412 is provided with a slot 413 which is closed by a cover 414. The cover 414 is held in place by a set screw 415. The cover 415 is provided with a slot 416 which is closed by a cover 417. The cover 417 is held in place by a set screw 418. The cover 418 is provided with a slot 419 which is closed by a cover 420. The cover 420 is held in place by a set screw 421. The cover 421 is provided with a slot 422 which is closed by a cover 423. The cover 423 is held in place by a set screw 424. The cover 424 is provided with a slot 425 which is closed by a cover 426. The cover 426 is held in place by a set screw 427. The cover 427 is provided with a slot 428 which is closed by a cover 429. The cover 429 is held in place by a set screw 430. The cover 430 is provided with a slot 431 which is closed by a cover 432. The cover 432 is held in place by a set screw 433. The cover 433 is provided with a slot 434 which is closed by a cover 435. The cover 435 is held in place by a set screw 436. The cover 436 is provided with a slot 437 which is closed by a cover 438. The cover 438 is held in place by a set screw 439. The cover 439 is provided with a slot 440 which is closed by a cover 441. The cover 441 is held in place by a set screw 442. The cover 442 is provided with a slot 443 which is closed by a cover 444. The cover 444 is held in place by a set screw 445. The cover 445 is provided with a slot 446 which is closed by a cover 447. The cover 447 is held in place by a set screw 448. The cover 448 is provided with a slot 449 which is closed by a cover 450. The cover 450 is held in place by a set screw 451. The cover 451 is provided with a slot 452 which is closed by a cover 453. The cover 453 is held in place by a set screw 454. The cover 454 is provided with a slot 455 which is closed by a cover 456. The cover 456 is held in place by a set screw 457. The cover 457 is provided with a slot 458 which is closed by a cover 459. The cover 459 is held in place by a set screw 460. The cover 460 is provided with a slot 461 which is closed by a cover 462. The cover 462 is held in place by a set screw 463. The cover 463 is provided with a slot 464 which is closed by a cover 465. The cover 465 is held in place by a set screw 466. The cover 466 is provided with a slot 467 which is closed by a cover 468. The cover 468 is held in place by a set screw 469. The cover 469 is provided with a slot 470 which is closed by a cover 471. The cover 471 is held in place by a set screw 472. The cover 472 is provided with a slot 473 which is closed by a cover 474. The cover 474 is held in place by a set screw 475. The cover 475 is provided with a slot 476 which is closed by a cover 477. The cover 477 is held in place by a set screw 478. The cover 478 is provided with a slot 479 which is closed by a cover 480. The cover 480 is held in place by a set screw 481. The cover 481 is provided with a slot 482 which is closed by a cover 483. The cover 483 is held in place by a set screw 484. The cover 484 is provided with a slot 485 which is closed by a cover 486. The cover 486 is held in place by a set screw 487. The cover 487 is provided with a slot 488 which is closed by a cover 489. The cover 489 is held in place by a set screw 490. The cover 490 is provided with a slot 491 which is closed by a cover 492. The cover 492 is held in place by a set screw 493. The cover 493 is provided with a slot 494 which is closed by a cover 495. The cover 495 is held in place by a set screw 496. The cover 496 is provided with a slot 497 which is closed by a cover 498. The cover 498 is held in place by a set screw 499. The cover 499 is provided with a slot 500 which is closed by a cover 501. The cover 501 is held in place by a set screw 502. The cover 502 is provided with a slot 503 which is closed by a cover 504. The cover 504 is held in place by a set screw 505. The cover 505 is provided with a slot 506 which is closed by a cover 507. The cover 507 is held in place by a set screw 508. The cover 508 is provided with a slot 509 which is closed by a cover 510. The cover 510 is held in place by a set screw 511. The cover 511 is provided with a slot 512 which is closed by a cover 513. The cover 513 is held in place by a set screw 514. The cover 514 is provided with a slot 515 which is closed by a cover 516. The cover 516 is held in place by a set screw 517. The cover 517 is provided with a slot 518 which is closed by a cover 519. The cover 519 is held in place by a set screw 520. The cover 520 is provided with a slot 521 which is closed by a cover 522. The cover 522 is held in place by a set screw 523. The cover 523 is provided with a slot 524 which is closed by a cover 525. The cover 525 is held in place by a set screw 526. The cover 526 is provided with a slot 527 which is closed by a cover 528. The cover 528 is held in place by a set screw 529. The cover 529 is provided with a slot 530 which is closed by a cover 531. The cover 531 is held in place by a set screw 532. The cover 532 is provided with a slot 533 which is closed by a cover 534. The cover 534 is held in place by a set screw 535. The cover 535 is provided with a slot 536 which is closed by a cover 537. The cover 537 is held in place by a set screw 538. The cover 538 is provided with a slot 539 which is closed by a cover 540. The cover 540 is held in place by a set screw 541. The cover 541 is provided with a slot 542 which is closed by a cover 543. The cover 543 is held in place by a set screw 544. The cover 544 is provided with a slot 545 which is closed by a cover 546. The cover 546 is held in place by a set screw 547. The cover 547 is provided with a slot 548 which is closed by a cover 549. The cover 549 is held in place by a set screw 550. The cover 550 is provided with a slot 551 which is closed by a cover 552. The cover 552 is held in place by a set screw 553. The cover 553 is provided with a slot 554 which is closed by a cover 555. The cover 555 is held in place by a set screw 556. The cover 556 is provided with a slot 557 which is closed by a cover 558. The cover 558 is held in place by a set screw 559. The cover 559 is provided with a slot 560 which is closed by a cover 561. The cover 561 is held in place by a set screw 562. The cover 562 is provided with a slot 563 which is closed by a cover 564. The cover 564 is held in place by a set screw 565. The cover 565 is provided with a slot 566 which is closed by a cover 567. The cover 567 is held in place by a set screw 568. The cover 568 is provided with a slot 569 which is closed by a cover 570. The cover 570 is held in place by a set screw 571. The cover 571 is provided with a slot 572 which is closed by a cover 573. The cover 573 is held in place by a set screw 574. The cover 574 is provided with a slot 575 which is closed by a cover 576. The cover 576 is held in place by a set screw 577. The cover 577 is provided with a slot 578 which is closed by a cover 579. The cover 579 is held in place by a set screw 580. The cover 580 is provided with a slot 581 which is closed by a cover 582. The cover 582 is held in place by a set screw 583. The cover 583 is provided with a slot 584 which is closed by a cover 585. The cover 585 is held in place by a set screw 586. The cover 586 is provided with a slot 587 which is closed by a cover 588. The cover 588 is held in place by a set screw 589. The cover 589 is provided with a slot 590 which is closed by a cover 591. The cover 591 is held in place by a set screw 592. The cover 592 is provided with a slot 593 which is closed by a cover 594. The cover 594 is held in place by a set screw 595. The cover 595 is provided with a slot 596 which is closed by a cover 597. The cover 597 is held in place by a set screw 598. The cover 598 is provided with a slot 599 which is closed by a cover 600. The cover 600 is held in place by a set screw 601. The cover 601 is provided with a slot 602 which is closed by a cover 603. The cover 603 is held in place by a set screw 604. The cover 604 is provided with a slot 605 which is closed by a cover 606. The cover 606 is held in place by a set screw 607. The cover 607 is provided with a slot 608 which is closed by a cover 609. The cover 609 is held in place by a set screw 610. The cover 610 is provided with a slot 611 which is closed by a cover 612. The cover 612 is held in place by a set screw 613. The cover 613 is provided with a slot 614 which is closed by a cover 615. The cover 615 is held in place by a set screw 616. The cover 616 is provided with a slot 617 which is closed by a cover 618. The cover 618 is held in place by a set screw 619. The cover 619 is provided with a slot 620 which is closed by a cover 621. The cover 621 is held in place by a set screw 622. The cover 622 is provided with a slot 623 which is closed by a cover 624. The cover 624 is held in place by a set screw 625. The cover 625 is provided with a slot 626 which is closed by a cover 627. The cover 627 is held in place by a set screw 628. The cover 628 is provided with a slot 629 which is closed by a cover 630. The cover 630 is held in place by a set screw 631. The cover 631 is provided with a slot 632 which is closed by a cover 633. The cover 633 is held in place by a set screw 634. The cover 634 is provided with a slot 635 which is closed by a cover 636. The cover 636 is held in place by a set screw 637. The cover 637 is provided with a slot 638 which is closed by a cover 639. The cover 639 is held in place by a set screw 640. The cover 640 is provided with a slot 641 which is closed by a cover 642. The cover 642 is held in place by a set screw 643. The cover 643 is provided with a slot 644 which is closed by a cover 645. The cover 645 is held in place by a set screw 646. The cover 646 is provided with a slot 647 which is closed by a cover 648. The cover 648 is held in place by a set screw 649. The cover 649 is provided with a slot 650 which is closed by a cover 651. The cover 651 is held in place by a set screw 652. The cover 652 is provided with a slot 653 which is closed by a cover 654. The cover 654 is held in place by a set screw 655. The cover 655 is provided with a slot 656 which is closed by a cover 657. The cover 657 is held in place by a set screw 658. The cover 658 is provided with a slot 659 which is closed by a cover 660. The cover 660 is held in place by a set screw 661. The cover 661 is provided with a slot 662 which is closed by a cover 663. The cover 663 is held in place by a set screw 664. The cover 664 is provided with a slot 665 which is closed by a cover 666. The cover 666 is held in place by a set screw 667. The cover 667 is provided with a slot 668 which is closed by a cover 669. The cover 669 is held in place by a set screw 670. The cover 670 is provided with a slot 671 which is closed by a cover 672. The cover 672 is held in place by a set screw 673. The cover 673 is provided with a slot 674 which is closed by a cover 675. The cover 675 is held in place by a set screw 676. The cover 676 is provided with a slot 677 which is closed by a cover 678. The cover 678 is held in place by a set screw 679. The cover 679 is provided with a slot 680 which is closed by a cover 681. The cover 681 is held in place by a set screw 682. The cover 682 is provided with a slot 683 which is closed by a cover 684. The cover 684 is held in place by a set screw 685. The cover 685 is provided with a slot 686 which is closed by a cover 687. The cover 687 is held in place by a set screw 688. The cover 688 is provided with a slot 689 which is closed by a cover 690. The cover 690 is held in place by a set screw 691. The cover 691 is provided with a slot 692 which is closed by a cover 693. The cover 693 is held in place by a set screw 694. The cover 694 is provided with a slot 695 which is closed by a cover 696. The cover 696 is held in place by a set screw 697. The cover 697 is provided with a slot 698 which is closed by a cover 699. The cover 699 is held in place by a set screw 700. The cover 700 is provided with a slot 701 which is closed by a cover 702. The cover 702 is held in place by a set screw 703. The cover 703 is provided with a slot 704 which is closed by a cover 705. The cover 705 is held in place by a

tance from the work. This distance may be changed by adjusting the spoon arm 45 along the shaft 43.

In operation a lap 8 is selected which is of a diameter corresponding to the holes in the work to be lapped, a cylindrical lap being selected for cylindrical holes. The work A is put in place and is held by the work holder 9, the work holder and plunger being ordinarily held in withdrawn positions by the latch 27 while the work is being put in place. The tailstock is bodily adjusted, as before described, so that the lap projects into and through the work and then the reciprocations of the plunger and work holder are started by releasing the latch 27 and allowing one of the cam followers 25 or 26 to engage the corresponding cam 20 or 21. Assuming that the cam 20 is engaged, the plunger with the work holder and work, is regularly reciprocated to effect lapping. If all four of the cam segments 51 are in place, as before described, the spoon 44 will be raised at each reciprocation to apply a charge of abrasive to the lap. If it is desired to apply abrasive less frequently, this can be effected by removing some of the cams 51 as before described. Excess abrasive can be discharged through the lower hole 10^b back to the pan 42. The operations, as before described, are continued until the hole is lapped to the desired size, whereupon the work A is removed and a new piece put in place.

35 The cam 21 can be used either for cylindrical holes or conical holes. When used for cylindrical holes it provides three short reciprocations followed by a long reciprocation, the abrasive being applied to the lap at the time of the long reciprocation.

When conical or tapered holes are to be lapped, a tapered lap is selected having the desired degree of taper and the tailstock is so adjusted that the work barely touches the lap at each of the shorter reciprocations. At each of the long reciprocations, the work is considerably withdrawn from the lap and abrasive is applied. The short reciprocations, whereby the work is repeatedly brought into momentary contact with the lap, are of the greatest importance in the lapping of tapered holes. In the case of cylindrical holes there is a uniform longitudinal reciprocation which prevents any scratching or scoring of the work by large particles of abrasive on the lap. Clearly, in the case of tapered holes, uniform longitudinal reciprocation is impossible and I avoid scratching or scoring by simply engaging the work with the lap momentarily and then withdrawing it so quickly that scratching or scoring cannot occur.

It will be understood that to properly perform the lapping operation, there must necessarily be relative reciprocatory and

rotary movements between the lap and work. As illustrated in the drawing, I rotatably mount the lapping spindle 4 in the headstock 2 in a manner to support the spindle rigidly against any movement except its rotation. The work spindle 10 is mounted for reciprocation within the tailstock 3 in a manner to support such spindle rigidly against any movement except its reciprocation. By thus making one spindle the rotary element and the other spindle the reciprocating element, both spindles may be more rigidly mounted in their supports than could be the case were one such spindle required to both rotate and reciprocate. Furthermore, by making the lapping spindle to rotate and the work spindle to reciprocate, work pieces may be removed from and inserted in the work spindle without stopping the rotation of the lapping spindle. Were the work spindle the rotary element, a stopping of the rotation thereof each time the work is to be changed would be necessary. To change the work in my machine, it is only necessary to stop the work spindle at the end of one of its backward reciprocations, the lapping spindle and other mechanism continuing to rotate. The particular driving arrangement from the rotating spindle 4 to the work spindle 10 is of advantage in securing the work changing functions just defined. Furthermore, as has been heretofore stated, the reciprocation of the work spindle from the rotation of the lapping spindle establishes a definite timed relation between the rotation and reciprocation of the lapping and work spindles respectively. Such a relative movement between the tool and the surface of the work being lapped finishes the work to a finer and smoother surface than may otherwise be obtained.

Furthermore, as has been specifically defined, the machine has provided in combination therewith with an automatically operating abrasive supplying mechanism. As illustrated in the drawing, this mechanism is constructed in the form of a spoon 44 adapted to intermittently dip an abrasive substance from a pan 42 and apply the same to the lap 8. This spoon is operated directly from the spindle operating mechanism whereby the same functions regularly in timed relation to the operation of the spindles. This spoon and its operating mechanism in combination with the spindles, as illustrated and defined, automatically applies abrasive to the lap at regular intervals without requiring any attention from the operator.

My invention, taken as a whole, provides a new and useful lapping machine combination having various improvements and advantages. The several parts of the machine are so arranged and constructed that

all function in timed relation to effect the lapping of work pieces in a most efficient manner. Furthermore, the several operating elements are all operably connected to and driven from the tool spindle 4 by the compact and novel mechanism illustrated and defined and hereinafter particularly pointed out in the claims appended hereto.

What I claim is:

10. 1. In a lapping machine, the combination of a work spindle, a cooperating tool spindle adapted to support a lapping tool thereon, means for rotating one of the spindles, and means for automatically reciprocating one of the spindles axially toward and from the other spindle once or a plurality of times during a predetermined rotation of the rotating spindle. 70
20. 2. In a lapping machine, the combination of a work spindle, a cooperating tool spindle adapted to support a lapping tool thereon, means for rotating one of the spindles, and means for giving one of the spindles either a long reciprocation or a plurality 75
25. of short reciprocations axially toward and from the other spindle during a predetermined rotation of the rotating spindle. 80
30. 3. In a lapping machine, the combination of a work spindle, a cooperating tool spindle adapted to support a lapping tool thereon, means for rotating one of the spindles, and means for giving one of the spindles either one long reciprocation or a plurality 85
35. of short reciprocations and one long reciprocation axially toward and from the other spindle during a predetermined rotation of the rotating spindle. 90
40. 4. In a lapping machine, the combination of a work spindle, a cooperating tool spindle adapted to support a lapping tool thereon, and separate selective operating means for giving one of the spindles one form of various different axial reciprocating movements. 95
45. 5. In a lapping machine, the combination of a work spindle, a cooperating tool spindle adapted to support the lapping tool thereon, and operating means comprising a plurality of cams adapted selectively to be used for giving one of the spindles one form 100
50. of various different axial reciprocating movements. 110
55. 6. In a lapping machine, the combination of a work spindle, a cooperating tool spindle adapted to support a lapping tool thereon, an operating shaft extending transversely of one spindle, a plurality of cams thereon, and means operatively connected to the said one spindle and adapted to be selectively operated by the cams for giving the said spindle one form of various different axial reciprocating movements corresponding to the respective cams. 115
60. 7. In a lapping machine, the combination of a work spindle, a cooperating tool spindle adapted to support a lapping tool thereon, means for rotating the tool spindle, a shaft extending longitudinally of the spindles, means connecting the tool spindle and shaft to rotate the latter, a driver secured to the shaft, a driven element meshing therewith, two cams operated by the driven element for reciprocating the work spindle axially, and means whereby either cam may be used to effect the said reciprocation. 120
70. 8. In a lapping machine, the combination of a work spindle, a cooperating tool spindle adapted to support a lapping tool thereon, means for rotating the tool spindle, a shaft extending longitudinally of the spindles, gearing connecting the tool spindle and shaft to rotate the latter, a worm secured to the shaft, a worm wheel meshing therewith, two cams operatively connected to the worm wheel, two cam followers secured to the work spindle, and means whereby either follower may be adjusted to engage its corresponding cam to effect axial reciprocation of the work spindle. 125
80. 9. In a lapping machine, the combination of a headstock and a tailstock, a tool spindle rotatably mounted in the headstock, means for rotating the tool spindle, a work spindle slidably mounted in the tailstock, means for adjusting the tailstock toward and from the headstock, a shaft extending longitudinally of the spindles, gearing connecting the tool spindle and shaft to rotate the latter, a worm splined to the shaft and longitudinally slideable therewith, a worm wheel meshing therewith, two cams operated by the worm wheel for reciprocating the work spindle, and means whereby either cam may be used to effect the said reciprocation. 130
90. 10. In a lapping machine, the combination of a work spindle, a cooperating tool spindle adapted to support a lapping tool thereon, means for reciprocating one of the spindles axially toward and from the other spindle, and means operated synchronously with the said reciprocating means for intermittently and automatically applying an abrasive substance to the lap. 135
11. In a lapping machine, the combination of a work spindle, a cooperating tool spindle adapted to support a lapping tool thereon, means for reciprocating one of the spindles axially toward and from the other spindle, a spoon for applying an abrasive substance to the lap, and means operated synchronously with the said reciprocations for operating the spoon to automatically carry a supply of abrasive substance to the lap. 140
12. In a lapping machine, the combination of a work spindle, a cooperating tool spindle adapted to support a lapping tool thereon, means for reciprocating one of the spindles axially toward and from the other spindle, an abrasive-containing trough below the work spindle, a spoon adapted to alternately engage in the trough and against the lap, 145

and means operated in timed relation with the spindle reciprocating means for intermittently operating the spoon.

13. In a lapping machine, the combination of a work spindle, a cooperating tool spindle adapted to support a lapping tool thereon, means for reciprocating one of the spindles axially toward and from the other spindle, an abrasive-containing trough below the work spindle, a spoon adapted to oscillate about a pivot to alternately engage in the trough and against the lap, and means operated in timed relation with the spindle reciprocating means for intermittently oscillating the spoon.

14. In a lapping machine, the combination of a work spindle, a cooperating tool spindle adapted to support a lapping tool thereon, means for reciprocating one of the spindles axially toward and from the other spindle, a spoon for applying an abrasive substance to the lap, and mechanism for automatically operating the spoon in timed relation to the spindle reciprocation and including means for changing the interval between successive movements of the spoon whereby to vary the amount of abrasive substance applied to the lap.

15. In a lapping machine, the combination of a work holder, a cooperating tool spindle adapted to support a lapping tool thereon, means for rotating the spindle, means providing an axial relative reciprocation between the spindle and holder, certain periodic reciprocations being longer than the others, and means for applying abrasive substance to the lap at said longer reciprocations.

16. In a lapping machine, the combination of a work holder, a cooperating tool spindle adapted to support a lapping tool thereon means for rotating the spindle, means providing an axial relative reciprocation between the spindle and holder to engage a lap within and to withdraw the same from the work, and means operated in timed relation with the reciprocation for applying abrasive substance to the lap while in its withdrawn position.

17. In a lapping machine, the combination of a work holder, a cooperating tool spindle adapted to support a lapping tool thereon, means for rotating the spindle, means providing an axial relative reciprocation between the spindle and holder to engage a lap within and to withdraw the same from the work, and means comprising a spoon operated in timed relation with the reciprocation to engage the spoon against the lap for applying abrasive substance to the lap while in its withdrawn position.

18. In a lapping machine, the combination of a work holder, a cooperating tool spindle adapted to support a lapping tool thereon, means for rotating the spindle,

means providing an axial relative reciprocation between the spindle and holder, a rod, a spoon for applying abrasive substance to the lap resiliently mounted on the rod, and mechanism whereby the rod is automatically rocked to operate the spoon in timed relation to the reciprocation.

19. In a lapping machine, the combination of a work holder, a cooperating tool spindle adapted to support a lapping tool thereon, means for rotating the spindle, means providing an axial relative reciprocation between the spindle and holder, a rod, a spoon resiliently mounted on the rod, a rocker arm secured to the rod, and a cam wheel engaging the rocker arm and operated in timed relation to the reciprocating means for operating the spoon to apply an abrasive substance to the lap.

20. In a lapping machine, the combination of a work spindle, a cooperating tool spindle adapted to support a lapping tool thereon, means for reciprocating one of the spindles axially toward and from the other spindle, means operated synchronously with the said reciprocating means for intermittently and automatically applying an abrasive substance to the lap, and means for varying the frequency of operation of the abrasive applying means relative to the said reciprocation.

21. In a lapping machine, the combination of a work spindle, a cooperating tool spindle adapted to support a lapping tool thereon, means for rotating one of the spindles, means for reciprocating one of the spindles axially toward and from the other spindle, an abrasive-containing trough below the work spindle, a spoon adapted to alternately engage in the trough and against the lap, means operated from the spindle reciprocating means for intermittently operating the spoon, and means for varying the frequency of operation of the spoon relative to the said reciprocation.

22. In a lapping machine, the combination of a work spindle, a cooperating tool spindle adapted to support a lapping tool thereon, means for rotating one of the spindles, means for reciprocating one of the spindles axially toward and from the other spindle, an abrasive-containing trough below the work spindle, a spoon adapted to alternately engage in the trough and against the lap, cam means operated from the spindle reciprocating means for intermittently operating the spoon, and means for varying the frequency of operation of the cam means on the spoon relative to the said reciprocation.

23. In a lapping machine, the combination of a bed, a horizontal spindle adapted to support a lapping tool thereon, means for rotating the spindle, a work holder, a shaft rotatably mounted in the bed,

means connecting the spindle and shaft for rotating the latter, a driver secured to the shaft, a driven element connected therewith and operatively connected with the work holder to reciprocate the same axially, a horizontal rod, a spoon for applying abrasive substance to the lap resiliently mounted on the rod, a rocker arm secured to the rod, and cam means operably connected to the said driven element and engaging the rocker arm for operating the spoon.

24. In a lapping machine, the combination of a bed, a horizontal spindle adapted to support a lapping tool thereon, means for rotating the spindle, a work

holder, a shaft rotatably mounted in the bed, gears connecting the spindle and shaft for rotating the latter, a worm secured to the shaft, a worm wheel meshing therewith, a cam connected to the worm wheel and adapted to reciprocate the work holder axially, a horizontal rod, a spoon for applying abrasive substance to the lap resiliently mounted on the rod, a rocker arm secured to the rod, and a cam operably connected to the worm wheel and engaging the rocker arm whereby to operate the spoon.

In testimony whereof I hereto affix my signature.

FRANK O. HOAGLAND.
